WINDOW SASH BALANCE

August Viehweger, New Paltz, N. Y., assignor to
Grand Rapids Hardware Company, Grand
Rapids, Mich., a corporation of Michigan

Application June 3, 1937, Serial No. 146,270

1 Claim. (Cl. 16—197)

This invention relates to a window sash balance and it aims to provide a novel construction, exceedingly compact, durable and unitary and adapted to be mortised in the side edges of the sash flush with the edges thereof.

It is further aimed to provide such a structure wherein the rotor or spiral element has a spiral groove, is somewhat springy, and operates in connection with a strip which extends into the same housing or casing which mounts the spiral element or rotor and associated spring mechanism.

Another object is to provide a novel construction which is simplified and avoids the necessity of employing a casing or housing to enclose the parts, and such a construction as will permit both sashes to be raised or lowered to the full limit permitted by the window frame.

The more specific objects and advantages will become apparent from a consideration of the description following taken in connection with accompanying drawings illustrating an operative embodiment.

In said drawings:

Figure 1 is a view, fragmentary, partly in front elevation and partly in section showing my improvement applied to window sashes and a window frame;

Figure 2 is a view through my sash balance with the casing or housing in section;

Figure 3 is an enlarged substantially central longitudinal sectional view through the device at the upper end;

Figure 4 is an enlarged substantially central longitudinal sectional view through the device at the lower end;

Figure 5 is a cross sectional view taken on the line 5—5 of Figure 2;

Figure 6 is a cross sectional view taken on the line 6—6 of Figure 4;

Figure 7 is a cross sectional view taken on the line 7—7 of Figure 2;

Figure 8 is a cross section taken on the line 8—8 of Figure 4;

Figure 9 is a fragmentary elevation, partly in section, showing a modified form of the invention;

Figure 10 is a view showing a window sash balance of the modified form alone and partly broken away to disclose details;

Figure 11 is a detail longitudinal sectional view through the upper portion of Figure 10;

Figure 12 is a longitudinal sectional view of the lower portion of Figure 10; and

Figure 13 is a detail cross section taken on the line 13—13 of Figure 10.

Referring specifically to the drawings wherein like reference characters designate like or similar parts throughout the different views, 10 represents conventional vertically slidable window sashes operatively mounted in a frame 11. Such sashes at each side are mortised at 12 and in each mortise, a balance device or unit generally designated 13 is disposed so as to be flush with the side edges of such sashes.

Each device or unit consists of a casing or 10 housing 14, of stamped or cast metal or other material as desired, preferably of the cross sectional shape best shown in Figures 5, 6 and 7. At the lower end of the housing, it has an extension 15 at the outer wall thereof and a bracket 16 is riveted or otherwise fastened at 17 to such wall. A bearing or socket member 18 is interfitted with such bracket by means of a journal 19.

A hollow spiral element 20 is adapted to rotate within the casing 14 and at its lower end surrounds and is fastened to the bearing 18 by means of a pin 21, passing through the spiral element. Said spiral element has a spiral groove 22 and the spiral element is of spring metal.

At the upper end of the casing or housing 14, 25 a bearing 23 is disposed and adjacent the same within the spiral element 20 is a bushing at 24 on which the spiral element is journaled. Bearing 23 is pinned or otherwise fastened at 25 to the casing against rotation.

A strip 26 is disposed for the most part within the housing 14 between the flat wall thereof and the spiral element and it has a projection 27 disposed in the groove 22. Such strip also has a lug or the equivalent 28 thereon adapted to be fastened by means of a screw or the like 29 passing through an opening 30 thereof and into the window frame 11, the strip 26 thus being rigidly fastened to the window frame while the remainder of the device is adapted to slide with the window 40 sash.

A rod 31 has its lower end journaled in a recess 32 of bearing 18 and at its upper end it extends through bearing 23, and is fastened immovably thereto as by means of a pin or the equivalent 33 extending through the bearing and an opening of a series of openings 34 in the rod 31. Surrounding the rod 31 is a coil spring 36 whose lower end is anchored at 37 to the bearing 18 and its other end is fastened as at 38 to the rod 31. The series of openings 34 permit an adjustable connection.

Since the spiral element 20 is a spring, it has a tendency to give and take in any movement up 55

and down of the sash. The window sashes can be shipped with the devices applied in the mortises.

In the operation of the device, the sashes may be moved up or down during which action, the spiral element 20 will rotate due to the interengagement of the projection 21 in the spiral groove thereof, winding or unwinding the spring 36 as the case may be, thus controlling its tension, and the balancing of the sash. It will be clear that the spring must be wound in opposite directions depending on whether the balances are applied to upper or lower sashes.

Referring now to the modified form disclosed in Figures 9 to 13, a window frame is shown at 11a in Figure 9, in which sashes 14a are vertically slidable. These sashes have countersunk into their longitudinal side edges, modified forms of window sash balances generally designated 40. This modified form of balance consists of a longitudinally split tube 41 having one end extended to form an attaching tang or plate 42, equipped with pointed spurs 43 adapted to penetrate the wood, the tang 42 having an opening 44 therethrough to accommodate a screw or other fastening 45 as used to secure the same to the window frame 11a.

The spiral element is shown at 46 and such spiral element is hollow, has a spiral groove 47 and is of spring metal so as to have a tendency 30 to give and take in any movement up and down of the sash.

Pinned or otherwise fastened at 48 in the upper end of the spiral element 46 is a block 49 having a socket 50, in which a shaft or rod 51 is journaled and which shaft or rod 51 is fastened by means of a pin 52 to an attaching bracket 53 adapted to be screwed or otherwise fastened as at 54 to the adjacent sash 14a. The tube 41 may be

made from a single sheet of metal bent into shape and it preferably has an inwardly struck lug or other projection at 55 which extends into the spiral groove 47. A coil spring 56 surrounds the rod or shaft 51 and has one end 58 anchored to the block or plug 49 while its opposite end is anchored at 60 to the shaft 51, beneath which is a washer 62, surrounding shaft 51 and resting on a bushing 52a resting on the bracket 53 to which the spiral element 41 is fastened by means of a 10 set screw at 63.

This modified form of the device will function generally like that previously described since the spring 56 may be placed under any desired tension and the brackets 42 and 53 attached to the frame 15 and to the sash.

Attention is called to the fact that this form of the invention avoids the use of the extra strip member as is necessary in connection with the first form of the invention.

Various changes may be resorted to provided they fall within the spirit and scope of the invention.

I claim as my invention:—

A sash balance of the class described having a 25 casing, a bracket at one end thereof, a bearing journaled on said brackets, a spiral element within the casing connected to the bearing, a bearing at the other end of the casing, a rod extending into the casing and fixed to the second mentioned 30 bearing, spring means within the spiral element surrounding said rod and fastened to the rod at one end and to the first mentioned bearing at the other end, a strip extending into the casing and movable relatively thereto, said spiral element 35 having a spiral groove, and means on the strip extending into said groove.

AUGUST VIEHWEGER.
